[57] CLAIM

The ornamental design for a wind driven electric generator, substantially as shown and described.

DESCRIPTION

FIG. 1 is a front elevational view of a wind driven electric generator showing my new design, with the shaft shown broken away to indicate indeterminate length; FIG. 2 is a top plan view of FIG. 1;

FIG. 3 is a reduced scale sectional view taken along line 3—3 of FIG. 1;

FIG. 4 is a sectional view taken along line 4—4 of FIG. 2;

FIG. 5 is a reduced scale sectional view taken along line 5—5 of FIG. 1;

FIG. 6 is a reduced scale sectional view taken along line 6—6 of FIG. 1;

FIG. 7 is a reduced scale sectional view taken along line 7—7 of FIG. 1;

FIG. 8 is a reduced scale bottom plan view of the clamp of FIG. 1; and

FIG. 9 is a reduced scale fragmentary side elevational view of the clamp of FIG. 1.
